UNITED STATES PATENT OFFICE

CHARLES A. STUART, OF KENOSHA, WISCONSIN, ASSIGNOR TO SIMMONS COMPANY, OF NEW YORK, N. Y., A CORPORATION OF DELAWARE

DESIGN FOR A BEDSTEAD CORNER POST

Application filed February 6, 1933. Serial No. 47,127. Term of patent 3½ years.

To all whom it may concern:

Be it known that I, CHARLES A. STUART, a citizen of the United States, residing in Kenosha, county of Kenosha, and State of Wisconsin, have invented a new, original, and ornamental Design for a Bedstead Corner Post, of which the following is a specification, reference being had to the accompanying drawing, forming a part thereof.

Fig. 1 is a side elevation of the bedstead corner post, showing my new design.

Fig. 2 is a cross section on the line 2—2 of Fig. 1.

I claim:—

The ornamental design for a bedstead corner post substantially as shown.

CHARLES A. STUART.
